UNITED STATES PATENT OFFICE.

JOHN MACKENZIE, OF MINNEAPOLIS, MINNESOTA, ASSIGNOR OF ONE-HALF TO
WALTER HEYNACHER, OF MINNEAPOLIS, MINNESOTA.

GAS PRODUCING AND HEATING APPLIANCE.

Application filed May 22, 1925. Serial No. 32,125.

My invention relates to improvements in gas producing and heating appliances, the same being particularly, though not exclusively, designed for use in connection with 5 heating plants for dwellings.

An object of the invention is to supply a relatively simple appliance for supplying gas to be burned in a heater, said means providing for the efficient combustion of such gas and for safety and convenience in the use of the appliance.

With the foregoing and other objects in view, which will appear in the following description, the invention resides in the novel combination and arrangement of parts and in the details of construction hereinafter described and claimed.

In the drawings, Fig. 1 is a view of an appliance embodying my invention, the same 20 being illustrated partly in elevation, and partly diagrammatically, portions of certain parts being broken away to disclose structure that otherwise would be concealed and Fig. 2 is a view mainly in plan, but partly in 25 diagram, the same illustrating the appliance shown in Fig. 1.

In the drawings, wherein similar reference characters are used to designate similar parts, A indicates a furnace in which a 30 burner 10 is placed, said furnace being supplied with a flue 11 for the discharge of burned gases therefrom. An air blower 12, driven by an electric motor 13, has its output divided by two air pipes 14, 15 leading therefrom. The air pipe 15 leads into the top of a closed tank 16 for liquid fuel, the terminal 35 of said pipe 15 comprising a flexible tube 15^a fitted with a float 17 at its free open end, said float being adapted to keep said end of said 40 tube submerged at a constant depth beneath the surface of the fluid. A gas lead 18 taking off from the top of the tank 16 conducts carbureted air from said tank to the burner 10. The air pipe 14, leading from the blower 45 12, connects with the gas lead 18 at a point near the burner 10 and mixes fresh air with the carbureted air in said lead. A hand valve 19 in the gas lead and a similar valve 20 in the air pipe 14, both only slightly in 50 advance of the junction between the air pipe 14 and the gas lead 18, provide for regulating the admixture of gas and air entering the burner 10. A pilot pipe 21 taking off from the gas lead 18 extends to the burner 10. Fitted in the gas lead 18 at a point between 55 the burner 10 and the junction between the air pipe 14 and the lead 18, is a cut-off valve 22, the stem 23 thereof being connected with an operating lever 24, supplied with a weight 25 for depressing said lever and closing said 60 valve. A chain 26 attached to the lever 24 is connected with an arm 27 on the shaft 28 of an operating mechanism B. This mechanism B, which is of conventional design, is actuated by an ordinary thermostatic device 65 C placed in the heated space, the arm 27 being adapted upon actuation of said mechanism B to swing through 180°. Swinging from upstanding position to pendant position, said arm 27 opens the valve 22 and, in 70 returning, allows said valve to be closed by the weight 25.

The motor 13 operates constantly in the absence of accidental interruption of the flow of current through the conductors 29, 30 to 75 said motor. The fan 12^a of the blower 12, driven by the motor 13, propels air into the air pipes 14, 15 only in quantity directly proportionate to the output of said pipes. Thus, it will be understood that when the cut-off valve 22 is closed, the action of the blower 12 merely produces enough carbureted air 80 to supply the pilot pipe 21 and when said cut-off valve 22 is open the action of said blower not only supplies the gas lead 18 with fresh 85 air from the pipe 14, but increases the production of carbureted air to supply the burner 10. In this connection attention is invited to a check valve 31 fitted in the gas lead 19 between the point where the pilot pipe 21 connects therewith and the junction between the air pipe 14 and said gas lead 18. This check 90 valve 31 operates to prevent back pressure in the gas lead 18 when the cut-off valve 22 is closed and avoids interference that otherwise would obtain in the production of carbureted air for additional outlets in advance of said check valve 31. One such additional outlet from said gas lead 18 may comprise a branch lead as at 32, which is shown feeding 95 into a water heater 33.

The blower 12 has an air ingress pipe 34 leading thereto, said pipe being disposed through part of its length within the flue 11. Air passing through this ingress pipe 34 is heated 100 with the result that heated air is carbureted in the tank 16 and heated fresh air is mixed, next to the burner 10, with the warm carbureted air in the lead 18. To increase the 105 temperature of the carbureted air in its pas- 110

sage from the tank 16 to the burner 10, a part of the gas lead 18 is disposed in near proximity to the flue 11. Thus it will be seen that by having a part of the air ingress pipe 34 within the flue 11 and a part of the gas lead 18 disposed closely against said flue at the outside thereof, I advantageously employ, in substantial amount, the heat from the flue that otherwise would be wasted.

10 To avoid wasting fuel and to avoid the danger of liberating carbureted air, I provide identical safety valves 35, one for each outlet from the gas lead 18. One valve is fitted in the gas lead 18 in advance of the point where 15 the pilot pipe 21 is connected therewith, another of said valves 35 being fitted in the branch lead 32 to the water heater 33. Each safety valve 35 includes a fulcrumed lever 36 connected with the valve stem 37 thereof, said 20 lever being supplied with a weight 38 for closing the valve and with an armature core 39 hanging in a solenoid winding 40. Each winding 40 of each valve 35 is included in the circuit of the motor 13 and said windings 25 are constructed to exert only sufficient attractive force upon their respective armature cores to barely hold the levers 36, against the action of the weights 38, in valve opening position. Said windings 40, deenergized 30 by an interruption of current in the motor circuit, permit the valves 35 to be closed by the weights 38. Resumption of current in said circuit, without the resetting of the valves 35 is attended only with the spinning 35 of the fan 12 and that entirely without effect since said valves prevent the delivery of any carbureted air from the appliance. With the current reestablished in the motor circuit, a user may tilt any one of the levers 36, against 40 the action of its weight 38, until the armature core 39, carried by said lever, is fully depressed. In such position of said armature core, the valve is open and said core disposed within its winding 40 where it will be held 45 by the attractive force thereof. Having opened the safety valve 35 for any given burner, such burner may be re-lighted.

Changes in the specific form of my invention, as herein disclosed, may be made within 50 the scope of what is claimed without departing from the spirit of my invention.

Having described my invention, what I claim as new and desire to protect by Letters Patent is:

55 1. The combination with a heater, of a burner within the heater, a blower, an electric motor for driving the same, air pipes leading from said blower and dividing the output thereof, a tank for liquid fuel, one of said air pipes issuing into the liquid in said tank, a lead for conducting carbureted air from said tank to said burner, an electrically controlled safety valve fitted in said carbureted air lead and connected in the motor circuit, 60 said valve being required to be opened manu-

ally, but adapted automatically to be held open during the maintenance of current in said circuit and automatically to close upon the interruption of such current, the other of said air pipes being connected with said carbureted air lead at a point between said valve and burner, a check valve in the carbureted air lead between the safety valve and the junction of said second air pipe with said carbureted air lead, said check valve acting to 70 permit only of the flow therethrough of carbureted air toward the burner, a pilot lead taking off from the carbureted air lead at a point between the safety valve and said check valve, a cut-off valve fitted in the carbureted air lead between the burner and the junction of said second air pipe with said carbureted air lead, and means for opening and closing said cut-off valve to put the burner 75 into and out of operation.

2. In combination, a burner, a blower, air pipes leading from said blower and dividing the output thereof, a tank for liquid fuel, one of said air pipes issuing into the liquid in said tank, a lead for conducting carbureted air from said tank to said burner, a cut-off valve in said carbureted air lead, the other of said pipes being connected with said lead at a point between said cut-off valve and tank, 80 and a check valve fitted in the carbureted air lead at a point between the tank and the junction of said second pipe with said carbureted air lead, said check valve being adapted to permit only of the passage of carbureted air 85 therethrough toward said burner.

3. In combination, a burner, a lead connected therewith, a normally constantly driven blower for propelling fluid fuel through said lead to said burner, an electric motor for driving said blower, an electrically controlled valve fitted in said lead, an electric circuit common to said motor and valve, said valve being required to be opened manually, but adapted automatically to be held open electrically upon the maintenance of current in 105 said circuit and automatically to close upon the interruption of such current.

4. In combination, a burner, a blower, air pipes leading from said blower and dividing the output thereof, a tank for liquid fuel, one of said air pipes issuing into the liquid in said tank, a lead for conducting carbureted air from said tank to said burner, the other of said pipes being connected with said lead at a point between the burner and tank, and a check valve fitted in said lead between the tank and the junction of said second pipe with said lead, said check valve being adapted to permit only of the passage of carbureted air 110 therethrough toward said burner.

5. The combination with a heater having a flue for the discharge of burned gases, of a burner, a blower, air pipes leading from said blower and dividing the output thereof, a tank for liquid fuel, one of said air pipes issuing into 115

the liquid in said tank, a lead for conducting carbureted air from said tank to the burner, the other of said pipes being connected with said lead at a point between the burner and 5 tank, an air ingress conduit for conducting air to the blower, said conduit and said carbureted air lead being associated with said flue to cause the contents thereof to be heated by the gases in the flue, whereby air going to 10 the tank is heated to promote the carburetion thereof and whereby the carbureted air and the air to be mixed therewith are heated to promote the admixture thereof and prepare the mixture for combustion at the burner.

15 6. In combination, a plurality of leads fed from a common source, a plurality of burners,

one for each lead, a normally constantly driven blower for propelling fuel through said leads to their respective burners, an electric motor for driving said blower, a plurality of 20 electrically controlled valves, one for each burner, each valve being fitted in the lead of its respective burner, an electric circuit common to said valves and motor, each valve being required to be opened manually, but adapted 25 automatically to be held open electrically upon the maintenance of current in said circuit and automatically to close upon the interruption of such current.

In testimony whereof, I have signed my 30 name to this specification.

JOHN MACKENZIE.
